UNITED STATES PATENT OFFICE.

OLIVER L. REISER, OF COLUMBUS, OHIO.

ATTACHMENT FOR ADDING-MACHINES.

1,295,795.

Specification of Letters Patent. Patented Feb. 25, 1919.

Application filed May 25, 1918. Serial No. 236,618.

To all whom it may concern:

Be it known that I, OLIVER L. REISER, a citizen of the United States, residing at Columbus, in the county of Franklin and State 5 of Ohio, have invented new and useful Improvements in Attachments for Adding-Machines, of which the following is a specification.

This invention relates to attachments for 10 adding machines, and more particularly to means for operating the arm connected with the main or actuating shaft, said arm being thrown to operative position by means of a foot lever or pedal.

15 One object is to provide a device which may readily be attached to a machine of an ordinary commercial type and which shall comprise a bracket or the like pivotally mounted, a foot lever, a rod connecting the 20 foot lever with the bracket, but being detachable with reference thereto, and means for throwing the rod out of engagement automatically, permitting the hand operated member of the machine to return to normal 25 position without taking the foot from the pedal.

With the foregoing and other objects in view, the invention consists in the novel construction, combination and arrangement of 30 elements hereinafter described and claimed.

In the drawings—

Figure 1 is a view of the attachment in side elevation as applied to a machine, the latter being shown in outline, together with 35 the stand.

Fig. 2 is a front elevation of the structure of Fig. 1.

Figs. 3 to 5 are perspective views, showing, respectively, an operating member, a rod for 40 actuating the same, and a guiding element for the rod.

The frame or casing of a machine of usual commercial type is designated 10 and the stand therefor is shown at 12, the actuating 45 rock shaft being designated 13, and the usual lever operated by hand for controlling the shaft 13 being designated 14.

In carrying out my invention I employ a bracket 15 comprising a downwardly extending member 16 and a horizontally extending member 17 projecting at an acute angle with member 16. The member 16 is provided with an aperture 18 permitting of the proper mounting of the bracket. The bracket carries a stud or the like designated 20 with 55 which the hook 21 of the rod 22 co-operates

for the purpose of actuating the bracket and thereby moving the usual arm 14 for the customary purpose, that is for recording totals and the like. Clamping means 24 are 60 provided at the end of arm 17 permitting of the positive engagement thereof with arm 14.

The rod 22 is pivotally connected at 26 with lever or pedal 27 operated by foot power, and this rod 22 is returned to normal 65 position when the foot is withdrawn from the pedal, by means of a spring 28. If the foot is withdrawn in the manner indicated the arm 14 will return to normal position 70 owing to the action of the spring within the machine, controlling said arm. If it is desired to retain the foot on the pedal, the machine may be operated in that manner by employing means for throwing off the hook member 21, placing it out of engagement 75 with stud 20. For this purpose I provide rod 22 with an offset portion 32 co-operating with a wheel 33 mounted in a bracket 34 supported by any suitable clamping device such as that shown at 35. The offset portion 80 32 is opposite the wheel and between the latter and the frame when the hook 21 is out of engagement, and is thrown to that position at the proper moment with reference to the operation of arm 14.

It will be observed that in the use of the device the operator may have both hands free for manipulating the work, and that the necessity for employing other power operated mechanism is avoided. An appreciable amount of time is also saved, since the operator does not have to move his hand back and forth between the work and the handle 14.

What is claimed is:

1. In a device of the class described, the combination with the operating arm of an adding machine or the like, of a bracket secured thereto and moving therewith, a stud carried by the bracket, a pivotally mounted 100 foot lever, a rod connecting the lever with the stud and bracket, and means for automatically throwing the rod out of engagement with the stud and bracket.

2. In a device of the class described, the combination with the actuating shaft of an adding machine or the like, and an actuating arm carried by said shaft, of a bracket operating with said arm, a stud carried by the bracket, a foot lever, a rod connected 105 with the foot lever and detachably connected with the stud and bracket, means for return- 110

ing the rod and foot lever to normal position when the foot lever is released, and means for automatically throwing the rod out of engagement with the stud and bracket without removing the foot from the lever.

3. In a device of the class described, the combination with the actuating shaft and actuating arm of an adding machine or the like, of a bracket moving with said arm, a 10 pivotally mounted foot lever, a rod pivotally connected with the foot lever and detachably connected with the stud and bracket,

and means for automatically throwing the rod out of engagement with the stud and bracket, said means last named including an 15 offset member carried by the rod, and means mounted on a stationary element and engaged by the offset member at a predetermined point in the effective movement of the rod and the actuating arm and shaft of the 20 machine.

In testimony whereof I affix my signature.

OLIVER L. REISER.
